Emil Wahl,
BY *John A. Diederichs,* ATTORNEY.

UNITED STATES PATENT OFFICE.

EMIL WAHL, OF PHILADELPHIA, PENNSYLVANIA.

CROCHET-NEEDLE HANDLE.

SPECIFICATION forming part of Letters Patent No. 268,442, dated December 5, 1882.

Application filed April 10, 1882. (No model.)

To all whom it may concern:

Be it known that I, EMIL WAHL, a citizen of the United States, residing in the city and county of Philadelphia, State of Pennsylvania, have invented a new and useful Improvement in Crochet-Needles, which improvement is fully set forth in the following specification and accompanying drawings, in which—

Figure 1 is a side elevation of the crochet-needle embodying my invention. Fig. 2 is a longitudinal section thereof. Figs. 3 and 4 are longitudinal sections of modifications thereof.

Similar letters of reference indicate corresponding parts in the several figures.

My invention consists in forming a crochet-needle whereby it is lengthened, and provided with two or more hooks, either of which may be employed, as desired.

Referring to the drawings, A represents the handle of a crochet-needle, formed of bone, ivory, or other suitable material, said handle being in one piece with a crochet-needle which terminates in the usual hook, a. The portion of the said handle opposite to the hook a is hollow, and that end of said handle is split in the longitudinal direction, forming jaws B B, the exterior face whereof is tapering and receives a tightening-sleeve, C, the widest part of the jaws being at the end of the handle, so that by moving the sleeve toward said end the jaws B are thereby compressed.

D represents a crochet-needle, formed of bone, ivory, or other suitable material, which has hooks b b' at opposite ends, and is inserted at one end in the hollow of the handle A, the jaws B B, compressed by the ferrule or sleeve C, serving to firmly hold said needle in position, so that the hook b may be used, the body of the needle A acting as the handle therefor. By loosening the sleeve the needle D may be withdrawn, reversed, reapplied and secured, in which case the hook b' is outside, and thus rendered serviceable. The hooks b b' are of different sizes and differ in size from the hook a, whereby the combined needle is adapted for different kinds of work or material. Furthermore, the needle D constitutes a continuation of the needle having hook a, and thus lengthens the latter.

If desired, the hooks b b' may be formed of metallic needles A' A'', which are secured to

a collar-rod, E, either needle being adapted to enter the body of the handle A, the jaws B B tightening against said collar E. An additional needle, F, having a split end or jaws, similar to the jaws B, is adapted to fit over either of the needles A' A'' which is outside of the needle A, the jaws of the needle F being compressed by a sleeve, similar to the sleeve C, 60 against the collar E, thus providing additional needles and lengthening the entire needle. (See Fig. 3.)

The needles A' A'' may be duplicated and a hollow coupling-piece, G, provided therefor, 65 said piece having jaws and tightening-sleeve at each end. A needle, F, is also employed, the several parts being arranged as in Fig. 4, thus increasing the length of the needle to a greater extent and providing many needles, 70 either hook of which may be brought into service, it being evident that a still longer needle with many more hooks may be built up; but in either case the hooks are duplicated or multiplied, and may be similar or various, and either 75 hook is adapted to render service.

Fig. 4 is a duplication of the handle, having a crochet-needle integral therewith at one end and made hollow and compressible at the other end, with supplementary reversible crochet-needles, and a coupling or splice-piece for uniting said duplicate parts for elongation purposes.

Having thus described my invention, what I claim as new, and desire to secure by Letters 85 Patent, is—

1. A crochet-needle handle having a crochet-needle integral therewith at one end and the other end made hollow and compressible, and provided with a band or tightening-sleeve and a double-pointed crochet-needle, either end whereof is adapted to be inserted in the hollow end of the handle and secured thereto.

2. A crochet-needle handle having a crochet-needle integral therewith at one end and the other end made hollow and compressible, in combination with a tightening device, and a crochet-needle adapted to be inserted in the hollow end of the handle and secured thereto by said tightening device.

EMIL WAHL.
